UNITED STATES PATENT OFFICE.

JAMES F. LINDLEY, JR., OF INDIANAPOLIS, INDIANA, ASSIGNOR TO T. B. LAYCOCK MANUFACTURING COMPANY, OF INDIANAPOLIS, INDIANA, A CORPORATION OF INDIANA.

DISPLAY-RACK FOR BEDSTEADS.

No. 858,733.

Specification of Letters Patent.

Patented July 2, 1907.

Application filed August 4, 1906. Serial No. 329,249.

To all whom it may concern:

Be it known that I, JAMES F. LINDLEY, Jr., a citizen of the United States, residing at Indianapolis, in the county of Marion and State of Indiana, have invented 5 certain new and useful Improvements in Display-Racks for Bedsteads, of which the following is a specification.

This invention relates to improvements in stands or racks for displaying furniture and particularly for 10 displaying iron bedsteads.

The object of the invention is to economize space in furniture stores where beds are displayed for sale and to provide means whereby the characteristic features of the beds displayed will be kept constantly in view, 15 and to provide means whereby a number of bedsteads can be displayed in practically the same room heretofore required for the display of a single bed, and to present the goods in a more attractive form than has been heretofore obtainable.

20 I accomplish the objects of the invention by the mechanism illustrated in the accompanying drawings in which—

Figure 1, is a front perspective view of my improved display rack with the bedsteads to be displayed thereon, shown in actual position in dotted lines. Fig. 2, 25 is a view in side elevation and partial vertical section of my invention; Fig. 3, a top plan view of same with the lowest bedstead also in plan view, and with dotted lines showing the manner in which the bed may be 30 swung on one leg as a pivot, from in front of the display rack, and Fig. 4, is a view in end elevation of a modified form of my invention whereby a double rack is produced.

Like characters of reference indicate like parts 35 throughout the several views of the drawings.

5 are the front posts of my improved rack which are approximately two feet in height, and 6 are the rear posts which are preferably approximately twice the height of the posts 5, and 7 are horizontal bars preferably formed of a gas pipe, which connect the posts 5 and 6. Secured to the top of the posts 5 and to the pipe 7 between the posts 5 and 6 are the holders 8 and 9, respectively. These are preferably cast rigidly to the post and pipe by pouring melted metal into suitably shaped molds wherein the pipe and post are inserted, in the manner which is common in the manufacture of iron bedsteads. Formed in the tops of the holders 8 and 9 are depressions forming receptacles to receive the lower ends of the bed-posts of the bed 45 which will be supported and exhibited from these holders, the depressions being for the purpose of preventing the accidental displacement of the bedstead. 50 10 is a post which is seated in a socket formed inter-

grally with the holder 9. The post 10 extends to a height equal to the post 6, and both of the posts 6 and 55 10 terminate with the holders 8 similar to the one on the post 5. The purpose of these holders on posts 6 and 10 is to support a second bedstead which will occupy a higher position than the one supported by the first described holders. The height of the holders on posts 6 60 and 10 is such as to elevate the second bedstead so it can be seen above the one on the holders next below it. 11 is a bar formed out of metal piping which connects the two top holders.

Each of my complete racks will comprise end frames 65 formed out of posts constructed and united in the manner above described, and there may be more than two of these frames, depending on the length of the display rack which it is desired to use. Where several tiers of beds will be required to display the full line which 70 is carried a long continuous rack may be used and will generally be preferable to a number of separate racks as the frames between the end ones need not be doubled as would be the case where a number of short racks were used together.

75 12 is a horizontal bar connecting the pipes 7 and bolted to said pipes just back of the front posts 5.

13, 13 are diagonal brace bars connecting the back posts 6 of two adjacent end frames. The bars 12 and 13 are sufficient to brace and stiffen the rack, and by 80 removing the bolts which connect them to their respective posts, the rack can be knocked down and closely nested for shipment and storage. The bars 12 and 13 are provided with a plurality of apertures 14 in order that sides of the racks may be adjusted to and 85 from each other to suit beds of different widths. The lower ends of the posts 5 are provided with the foot pieces 15, and in addition they may have roller casters if desired though none are shown in the drawings, and these will generally not be required.

90 16 is a holder which is preferably cast integral with the front foot piece under the left post, and this holder is for the purpose of receiving the lower end of the post of a third bed the other posts of which will rest upon the floor of the display room. This bed will stand normally in front of the above described display rack and when it is desired to remove this third bed so that it will not obstruct the view of the rack and beds back of it, it can be swung around on that post which is seated in the holder 16, in the manner as is shown in plan view 100 in Fig. 3.

In the modification shown in Fig. 4, the post 5 is 105 duplicated on each side of the high back posts and the pipe 7 is extended to connect the extra posts with the others, and the additional holders 20 and 21 will be provided to receive a fourth bedstead. A stand of the

character here described is desirable where the display room will permit of access to the rack from two sides, that is, from the front and rear.

Having thus fully described my invention, what I claim as new and wish to secure by Letters Patent of the United States, is—

1. A rack for displaying bedsteads, comprising a plurality of vertical frames, means for holding the frames the width of a bed apart, said frames having a plurality of 10 pairs of holders, each pair in the same frame being at different altitudes, said holders having indentations in their upper sides to receive a bed post.

2. A rack for displaying bedsteads, comprising a plurality of vertical frames, horizontal and diagonal bars for 15 holding the frames the width of a bed apart, holders in horizontal pairs in a plurality of horizontal planes of said frames, said holders having top recesses to receive the end of a bed post.

3. A bedstead display rack comprising a plurality of 20 vertical posts terminating at their upper ends with holders having top indentations to receive the ends of the bed posts, said holders being in pairs of a plurality of altitudes in each rack and means for connecting the several posts of a rack in a rigid manner.

25 4. In a rack for displaying beds, a pair of vertical front posts and a pair of vertical back posts approximately twice the height of the front posts, horizontal pipes con-

nected the front and back posts in pairs, auxiliary posts between the front and back posts supported by the pipe and extending the same height as the back post, holders 30 terminating each of said pipes, said holders having top recesses and a holder at the base of the auxiliary posts, said posts forming end frames, and means for connecting said end frames together in pairs.

5. A rack for displaying bedsteads, comprising a plural- 35 ity of vertical frames, means for holding the frames the width of a bed apart, said frame having a plurality of holders with top indentations to receive a bed post, one of said holders being in front of one of the front posts of the rack at the lower end of said post.

6. A bedstead display rack comprising a plurality of 40 vertical posts terminating at their upper ends with holders having top indentations to receive the ends of the bed posts, said holders being in pairs and each pair lying in different planes above one another, means for connecting 45 the sides of the racks together, and means permitting the sides of the racks to be changed with relation to one another.

In witness whereof, I, have hereunto set my hand and seal at Indianapolis, Indiana, this, 24th day of July, A. D. 50 one thousand nine hundred and six.

JAMES F. LINDLEY, JR. [L. S.]
